CHANNELING-MACHINE.

1,130,660.

Specification of Letters Patent.

Patented Mar. 2, 1915.

Application filed August 3, 1906. Serial No. 329,004.

To all whom it may concern:

Be it known that we, ALBERT BALL and HENRY H. MERCER, both citizens of the United States, and residents of Claremont, 5 in the county of Sullivan and State of New Hampshire, have invented an Improvement in Channeling-Machines, of which the following description, in connection with the accompanying drawings, is a specification, 10 like letters on the drawings representing like parts.

Our invention relates to stone-working machines, the purpose thereof being to increase the effectiveness of such machines.

15 While this invention may be applied to stone-working machines of various types and for various purposes, it is here illustrated as applied to a track channeling machine constructed not only for cutting the 20 usual channel groove, but specially adapted for corner-cutting, that is, the cutting of the channel groove into the acute angle or corner underlying the inclined side of a quarry wall.

25 In the specific embodiment of our invention the corner-cutting is effected by so mounting the tool support that, while operating as usual in the open part of the quarry it may be made to cut from a fixed 30 position of the machine under the overhanging side-walls while the tool swings along the arc of a circle lengthening the channel groove, delivering its blows perpendicularly to the bottom of the groove and thereby 35 losing none of the effectiveness of its cutting stroke.

Our invention, having as it does other objects both connected with and disconnected from the above-mentioned aim, will be best 40 understood by reference to the following description, when taken in connection with the accompanying illustration of one specific embodiment thereof, while its scope will be more particularly pointed out in the appended claims:

45 In the drawings:—Figure 1 is a central transverse sectional elevation of a channeling machine embodying one form of our invention; Fig. 2 is a view, diagrammatic in 50 its nature, showing the manner in which the machine may be used for corner-cutting; Fig. 3 is a front elevation of the channeling machine shown in Fig. 1; Fig. 4 is a plan view taken in section on the irregular sec-

tion line 4—4 in Fig. 1, and Fig. 5 is a sectional detail on the line 5—5, Fig. 3, showing the locking pin.

Referring to the drawings and to the embodiment of our invention there submitted for illustrative purposes, the track channeling machine there shown is supported upon a frame work A which has journaled at opposite ends the two transverse shafts a, carrying at their outer ends two pairs of flanged trucks a', the latter tracking with 60 the rails b, which are customarily laid upon the quarry bottom, and along which the machine, when cutting in the usual fashion is advanced.

The machine carries suitable tool-reciprocating motive means, which may be of any suitable form but which is here shown as a compressed air direct acting engine, supplied with pressure from a suitable source (not shown) and having the piston c, cylinder C and the cross-head guides D. The cross-head E, which is connected to the piston by the piston-rod c', has clamped thereto a suitable tool or tools, such as the gang e of three channeling-tools shown 80 partly broken away, the cutting ends of the latter, therefore, being given a reciprocatory cutting movement to and from the bottom of the channel groove with the reciprocations of the engine piston. For adjustably feeding the tool toward the work as the channel groove deepens the engine cylinder and cross-head guides which are connected to move as an unit, are carried by the cutter head or standard F, and may be advanced along its face by means of the fixed nut c² on the cylinder and engaged by the longitudinal adjusting screw c³, which latter at its upper end is journaled in an extension f of the cutter-head.

95 The cutter-head (Fig. 4) is provided with suitable guiding ribs or flanges f' on which the engine cylinder and the attached cross-head guides are slidably retained by the gibs f² and along which they may be adjusted longitudinally by the adjusting screw c³. The latter at its upper end is provided with a head f³ through which, by the attachment of a suitable tool or implement, such as the ratchet lever f⁴ (Fig. 1), the screw may be turned and the engine and cross-head advanced toward the work as the channel groove deepens.

To obtain the swinging movement of the tool lengthwise the channel groove during corner cutting, the cutter-head F is supported at the side of the machine upon an oscillating or swinging support G, the latter comprising a circular plate or casting, having formed in its face (Figs. 3 and 4) a longitudinal guide way, in which the standard is adjustably clamped by means of the clamping-plates f^5 , which are bolted to the plate G. The clamping-plates hold the standard in fixed position, but the clamping-bolts may be loosened to permit it to be adjusted longitudinally, so that the entire standard with its attached cutting appliances may be dropped or advanced toward the work and clamped in this advanced position, as represented for example in Fig. 2. The clamping-plates preferably extend, as shown, across the entire face of the supporting plate G, so that when the standard is adjusted to a more advanced position it is maintained in accurate alignment with reference to the center of the plate, the axis of tool action lying preferably across the oscillation center of the plate.

In order to provide an oscillating or swinging movement for the cutter-head and the tool when the machine is employed for corner-cutting, the support G is mounted to swing through any desired arc in the main supporting-frame H, which latter is mounted at the side of the machine, as shown in Fig. 1. To permit the oscillating movement of the cutting parts the plate G has the centrally formed trunnion g journaled in a bearing h formed in the frame H, the said bearing being provided with the removable lining h' . The plate is held in position by the cap g' , fastened to the trunnion by the bolt g^2 and prevented from turning thereon by the pin g^3 .

When angle-cutting is desired, the main frame H, is adjustable about an axis lengthwise the channel groove so that it may be inclined backward, away from the vertical. To permit this adjustment it is fixedly secured at its base to trunnions h^2 journaled in the main frame A. It is held fixed in either an upright or an inclined position as may be desired during cutting by any suitable means, such as the inclined brace-rod I, the latter linked at its upper end to an ear h^3 upon the back of the frame H and at its lower end to an ear i carried by a bracket i' removably bolted to a seat upon the main frame A. The brace-rod I is formed in two separate pieces and provided with a suitable turnbuckle connection i^2 , by means of which its length may be taken up or extended to permit the necessary adjustment of the supporting-frame.

For reciprocating or oscillating the cutter-head during corner-cutting, the back of the oscillating plate G is bolted to a cir-

cular actuating device such as the annular worm gear J, meshing with an underlying driving worm j , the axis of the latter being coincident with the swinging axis of the frame H, so that the worm remains in proper mesh with its gear irrespective of the adjustment of the plate upon the trunnions h^2 . The back face of the plate G near its edges has a sliding contact with the main supporting frame H at h^4 , so that there is formed, in effect, a housing for the worm gear, protecting the latter from dust and dirt.

The worm j , is fixed upon the worm-shaft j' , journaled in suitable boxes h^5 at the base of the frame H. At each end the worm-shaft has a step or thrust bearing against the adjacent trunnion h^2 , there being also preferably provided at one end an adjustable thrust bearing K. The latter comprises one or more bearing washers k , retained within the sleeve k' between the end of the worm-shaft and the end of the trunnion. The sleeve k' is threaded on the end of the trunnion so that the wear of the bearing washers may be taken up, a suitable check-nut k^2 being provided to lock the same into position.

Any suitable means either manual or power driven for giving reciprocating driving movement to the worm gear J may be employed, but herein we have shown a special motive device comprising the tool-actuating fluid pressure engine L which turns the transverse driving-shaft l . The engine 100 is connected by the flexible hose connection l^2 to the source of compressed air supply (not shown) and is controlled as to speed by the throttle-valve l^3 (Fig. 4). The transverse shaft l carries at its end the beveled pinion m , which imparts opposite but equal rotation to the two beveled gears m' and m^2 . These may be separately clutched to or unclutched from the clutch-shaft m^3 by the sliding movement of the double clutch-member m^4 . The movement of the latter is effected through the shifting actuator m^5 (shown only in Fig. 4), connected to the hand-lever m^6 , the handle of which is conveniently positioned for grasp by the operator. The clutch member may be shifted by the hand-lever to clutch either the gear m' or the gear m^2 to the shaft m^3 , or left in an intermediate position wherein neither gear engages the shaft and the latter remains stationary.

The shaft m^3 has a pinion m^7 which meshes with the gear m^8 on the counter-shaft m^9 , the latter journaled in a bracket m^{10} on the machine frame. The counter-shaft also carries a gear m^{11} , meshing with the idle gear m^{12} , the latter engaging directly with the gear m^{13} which is fast upon and acts to drive directly the worm-shaft j' .

By the described transmission gearing the 130

tool-actuating engine L, when in operation, turns the worm-shaft and causes a comparatively slow swinging movement of the cutter-head upon its trunnion simultaneously 5 with the rapid chopping action of the tool under the influence of the tool engine C. When the swinging movement has advanced far enough in one direction the actuator m^5 may be thrown and the swinging movement 10 reversed. A power actuation of the swinging support is preferable since it not only renders the machine more mechanical but better insures a uniform swinging movement and the preservation therefore of a 15 true arc at the bottom of the channel groove.

During the cutting of the ordinary channel groove the channeler is caused to traverse the trackway as usual and the cutter-head is held fixed in the usual fashion. To 20 throw out the oscillating movement of the cutter-head under such conditions the idle gear m^{12} is slidably mounted on the stud m^{14} , so that, when desired, it may be slipped out of mesh with its two engaging gears 25 m^{11} and m^{13} , and the transmission gearing thereby thrown out of engagement. This leaves the cutter-head fixed in position, the worm holding it against movement. If desired, a locking-pin h^6 (Fig. 3) may be used 30 to effectually lock the swinging plate against movement relatively to the supporting-frame H.

During the cutting of the ordinary channel groove the necessary traversing movement is given to the machine carriage 35 through the clutch-shaft m^3 , which carries at each end a worm n meshing with an underlying worm gear n' secured to a carriage-shaft a . Through this means the carriage may be moved under its own power 40 along the rails in either direction, according to the position of the clutch m^4 , the same power driven member, namely, the shaft l acting to swing the tool or advance the carriage 45 as may be required.

During corner-cutting it is desirable to maintain the carriage stationary, and we have herein shown means for lifting the trucks of the machine clear from the track 50 and there rigidly holding the machine during the swinging movements of the tool. For this purpose there is provided at each corner of the machine frame a lug O, which lugs are vertically threaded to receive the 55 jack-screws o (Fig. 3), the latter having feet which align with the top of the rails. The enlarged feet of these screws fit a socket in a split clamp o' , the two halves of which may be clamped securely to the under side 60 of the tread of the rail by the transverse clamping screw o^2 . When the clamping screw is tightened the clamps grip the rail, preventing movement of the machine. Before clamping, the jack-screws are turned 65 to lift the machine high enough to free the

truck wheels from the rails. When corner-cutting has been completed the machine is again lowered upon its tracks and the clamps loosened.

Obviously, other means may be employed 70 to support the machine during corner-cutting, and if desired the jack-screws may rest directly upon the quarry bottom or in holes drilled in the quarry bottom.

In the operation of the machine, the 75 main portion of the channel groove is cut in the ordinary fashion with the supporting-frame held either vertically or inclined backward for angle-cutting. The overhanging side of the wall of the quarry, however, determines the limit of vertical cutting and when this is reached the machine is clamped 80 to the rails, the worm gear turned to tilt the cutter-head forward at any desired angle, and the tool then given, in addition to its usual reciprocatory movement to and from the work, an oscillating movement as well through any desired angle, so that the tool travels lengthwise the channel groove 85 in an arc-like path and its blows are delivered radially from the center of oscillation of the cutter-head. For example, referring to Fig. 2, the machine there shown is clamped to the rails B and engaged in making the corner cuts for a channel groove 90 transverse to the previously completed channel grooves 1, 2, 3 and 4, which with the exception of the groove 1, have been cut upon an angle. As represented in Fig. 2, the cutter-head has been swung forward by 100 movement of the worm gear and is being oscillated by the tool-actuating engine L through the angle between the channel grooves 3 and 4, successive cuts being represented by the dotted arcs 5. After the tool has cut to the bottom of groove 3, the bottom of the new transverse groove is left flat or horizontally by stopping the return swing of the tool short of the full angle.

It will be seen that the described machine is 110 quite universal in its construction, and, the tool carrier being sustained at substantially a mid position lengthwise the machine, so that it may be forwardly inclined from either end, corner-cutting from either end thereof, and at any angle which practical quarry requirements demand, may be readily effected without necessary change in adjustment of the supporting frame H. The construction and shape of the machine 115 furthermore permit its construction at a very low height, so that it can be moved well into the corner of an inclined quarry wall.

The adjustment of the cutter-head to and from the work which is permitted by the clamping-plates H permits the corner-cutting to be done, particularly at extreme angles, with tools of much lesser length, since by this adjustment the cross head may be brought in substantially the same close re- 125 130

lation to the rock in corner-cutting and angle cutting as in upright cutting. This will be evident from an inspection of Fig. 2, and still more by reference to an assumed position of the frame H for angle cutting, as for example, along the dotted line α — α , which evidently will cause the tool to strike the rock at some distance from the side of the carriage. This adjustment renders the tools easier to handle, as well as effecting a saving in their cost. For example, in the described machine a saving of 25 per cent. in the weight and length of the tools may be effected through this adjustment when cutting at an angle of 34° for the corner of an upright cut approximately six feet deep. This adjustment, inasmuch as it lowers the standard (see Fig. 2) also decreases the height of the machine when corner-cutting, permitting it to be advanced further into the corner.

While we have shown and described one form of our invention for the purpose of illustrating the same, it is to be understood in details of construction and relative arrangement of parts, as well as the application here made of the invention, the described embodiment may be widely deviated from without departing from the spirit of the invention.

Claim—

1. A channeling machine having cutting means, an oscillating or swinging carrier for said cutting means mounted to swing lengthwise the channel groove, a support on which said carrier is pivoted, said support being adjustable for tipping movement about an axis lengthwise the channel groove, a worm gear secured to said carrier and a worm engaging the same, the latter being in line with the tipping axis of the support.

2. A channeling machine having a reciprocatory tool adapted to swing lengthwise the channel groove, means to adjust the inclination of its swinging plane and a worm for effecting swinging movement, the said worm being in line with the axis about which adjustment takes place.

3. A channeling machine having a reciprocatory tool adapted to swing lengthwise the channel groove while undergoing reciprocation, means to adjust its plane of swinging movement, a worm for effecting swinging movement alined with the axis of adjustment, a motive device, and transmission gearing between said motive device and said worm.

4. A channeling machine having cutting means, means for imparting cutting movement thereto, said cutting means being adapted to swing lengthwise the channel groove, means to adjust the plane of swinging movement, a worm for effecting swinging movement, said worm being in line with the axis of adjustment, a motive device for

effecting swinging movement, transmission gearing between said motive device and said worm and means for reversing the direction of swinging movement.

5. A channeling machine adapted to be moved progressively for cutting an ordinary channel groove, power driven means upon the machine for imparting progressive movement thereto, means for maintaining said carriage stationary and means for giving the tool a swinging movement for corner cutting while the carriage is stationary.

6. A channeling machine having a carriage, power-operated means for moving the carriage, power-operated means for swinging the channeling tool lengthwise the channel groove, and means for throwing either of said means into or out of operation at will.

7. A channeling machine having a channeling tool, power operated means for swinging said channeling tool lengthwise the channel groove, transmission gearing between said power operated means and said tool swinging means, and means for throwing the gearing out of engagement.

8. A channeling machine having a carriage provided with trucks, a power operated member provided with suitably controlled devices for reversing its movement, driving connections between the trucks and said member, a channeling tool mounted for swinging movement and driving connections also from said member for swinging said tool.

9. A channeling machine having a carriage, a main trunnioned supporting frame at the side of the carriage, a supporting plate swiveled in the frame, in a substantially midway position lengthwise the carriage, a standard secured to the side of the plate, an engine crosshead, and crosshead guides on the standard, means for adjustably feeding the engine and crosshead guides toward the work, clamping plates by which the standard is clamped to the swivel plate but permitting its adjustment to position the cutting appliances nearer to or farther from the work and motor driven means to impart swinging movement to the swiveled plate.

10. A channeling machine having a swiveled supporting plate, a standard secured to the side of the plate, engine crosshead and crosshead guides on the standard, means for adjustably feeding the engine and crosshead guides toward the work, means by which the standard is held adjustably clamped to the swivel plate but capable of adjustment to position the cutting appliances nearer to or farther from the work and motor driven means for imparting swinging movement to the swiveled plate simultaneously with the cutting movement of the channeling tool.

11. A channeling machine having a swiveled support, a tool carrier thereon, means to adjustably feed the tool on the carrier toward or from the work, means to adjust 5 the carrier on the support toward or from the work, and motor driven means to swing the support simultaneously with the cutting movement of the tool. 70
12. A channeling machine having a standard, an engine together with its crosshead and crosshead guides thereon, means for adjustably feeding the latter on the standard toward the work, a support for said standard provided with suitable guideways extending 10 in the direction of engine feed, and clamping plates by which said standard may be clamped upon said support at selected positions along said guide-ways. 75
13. A channeling machine having a reciprocating tool, a support therefor, means to swing the tool lengthwise the channel groove during its reciprocation to cut under an oblique sidewall at and beyond the end of the machine, means to feed the tool toward 15 the work, and means to advance the tool support toward the work to shorten the necessary length of the tool when cutting at an inclination. 80
14. A channeling machine having a reciprocating tool, means for swinging the tool lengthwise the channel groove during the reciprocation in a path extending beyond the end of the machine, a support for the tool adjustable about an axis lengthwise 20 the channel groove, tool feeding means, a tool carrier, and means for adjusting the carrier to shorten the necessary length of the tool on angle cutting. 85
15. A channeling machine having a carriage, a swiveled support at its side, means for swinging the support reciprocably during the cutting operation, a standard on said support, means providing for an adjustment of the standard to advance its position toward the work and means forcibly to feed the tool toward the work, the line of tool feeding and standard advancement 25 lying across the axis of the support. 90
16. A channeling machine having a carriage, a tool carrying support swiveled at the side of the carriage and in a substantially central position lengthwise the same, and motor driven means to swing the support reciprocatively in either direction simultaneously with the reciprocations of the tool. 95
17. A channeling machine having a swiveled tool carrier, a support on which said carrier is secured, said support being adjustable about an axis lengthwise the channel groove, a worm in line with the axis of adjustment of said support for swinging said carrier, and a thrust bearing for said worm. 105
18. A channeling machine having a swiveled tool carrier, a circular actuating device attached thereto, and motor driven means for turning said actuator reciprocatively in either direction and said tool carrier about the axis of the latter. 110
19. A channeling machine having a swiveled tool carrier, a circular actuating device secured thereto, a support for said carrier adjustable about an axis lengthwise the channel groove, and a rotary power transmission member connected to turn said actuating device, said member being in line with the axis of adjustment of said support. 115
20. A channeler comprising a wheeled truck, a drill pivoted thereon, means for locking the drill to and releasing it from the truck, a motor and means for connecting the motor at will to the truck for driving the truck to cause the drill to cut a channel to a predetermined point while the drill is locked to the truck, and means for connecting the motor at will to the drill for swinging the drill in the arc of a circle to cause it to complete the channel from said predetermined point when the drill is released from the truck. 120
21. A channeler comprising a wheeled truck, a drill pivoted thereon, means for locking the drill to and releasing it from the truck, a motor mounted on the truck, and means for connecting the motor at will to the truck for driving the truck to cause the drill to cut a channel to a predetermined point while the drill is locked to the truck and means for connecting the motor at will to the drill for swinging the drill in the arc of a circle to cause it to complete the channel from said predetermined point when the drill is released from the truck. 125
22. A channeler comprising a wheeled truck, a tool pivoted thereon, means for swinging the tool in the arc of a circle to cause the tool to complete the channel, a support upon which the tool may be fed toward the work, means for feeding the tool on the support, and means also for adjusting said support toward or from the work. 130
23. A channeler comprising a wheeled truck, a tool mounted thereon, means for swinging the tool in the arc of a circle to cause the same to complete the channel, means for feeding the tool toward the work, and means independent thereof for also advancing the tool toward the work. 135
24. A channeler comprising a wheeled truck, a tool pivoted thereon, means for swinging the tool in the arc of a circle to complete the channel, tool feeding means, a tool carrier, and means for adjusting the carrier to shorten the necessary length of the tool while completing the channel. 140
25. A channeler comprising a wheeled truck, a drill pivoted thereon, a truck driving mechanism, a drill swinging mechanism, a driving motor common to said two mecha- 145

6
nisms, and means for rendering one or the other of said mechanisms at pleasure effective for applying the power of said motor to drive the truck or swing the drill respectively.

26. A channeler comprising a wheeled truck, a drill pivoted thereon, a truck driving mechanism, a drill swinging mechanism, a common motor, and means for rendering said motor effective or ineffective at pleasure for driving said truck or for swinging said drill.

10 27. A channeler comprising a wheeled truck, a drill pivoted thereon, a truck driving mechanism, a drill swinging mechanism, a driving motor mounted on the truck for said truck driving mechanism, and means for connecting the motor with or disconnecting the same from the drill swinging mechanism.

15 28. A channeler comprising a wheeled truck, a drill pivoted thereon, means for moving the truck to cause the drill to cut a channel to a predetermined point, means for swinging the drill in the arc of a circle to cause the drill to complete the channel from said predetermined point, a common motor mounted on the truck, and means for rendering either said truck moving means 20 or drill swinging means effective at will to apply the power of said motor to the moving of the truck or the swinging of the drill.

25 29. A channeler comprising a wheeled truck, a frame hinged thereto, a drill, its shell pivoted on the frame, means for adjusting the frame into different angular positions with respect to the truck, means for driving the truck to cause the drill to cut a channel to a predetermined point, means for swinging the drill in the arc of a circle to cause it to complete the channel from said predetermined point, a common motor mounted on the truck, and means for rendering either said truck driving means 30 or said drill swinging means effective at will for applying the power of said motor to driving the truck or swinging the drill.

35 30. In a channeling machine, the combination with a percussive tool, of a carrier for the same, means for adjustably feeding the tool on the carrier toward the work, a support, means for adjusting the carrier on the support to further advance the tool toward the work, and means for swinging the carrier and tool over the quarry bottom and beyond the base of the machine.

40 31. In a channeling machine, the combination with a frame, means for rigidly fixing the same in position, a support pivotally mounted on the frame, a tool carrier mounted for adjustable movement on the support toward or away from the work, a percussive tool and tool-actuating devices on the carrier, means including a feed screw and 45 coöperating parts for feeding the tool and

tool-actuating means on the carrier toward or from the work, and means for swinging the support about its pivotal connection to the fixed frame through a path of sufficient extent to cause it to cut beyond the frame. 70

32. In a channeling machine, the combination with means permitting the same to be progressively moved along the quarry bottom, power-driven means upon the machine for effecting its progressive movement, 75 means for stationarily and positively securing the machine at a fixed position on the quarry bottom, cutting means on the machine, means for holding the cutting means fixed on the machine while the latter is in motion, and motor driven means for moving the cutting means while the machine is held fixed.

33. A channeling machine provided with a percussive cutting tool having a reciprocatory movement to and from the work, a carriage, a tool-carrying support swiveled at the side of the carriage and in a substantially central position lengthwise the same, and means to swing the support simultaneously with the cutting operation of the tool through a path of sufficient extent to cut a groove beyond the carriage in either direction. 85

34. A channeling machine having, in combination, the wheeled truck A, the tool-carrying standard F, the swinging support G upon which the standard is mounted, the main supporting frame H upon which the support is sustained for swinging movement, and motor driven means for swinging the support. 95

35. A channeling machine having, in combination, the wheeled truck A, the reciprocatory tool, the standard F, carrying the 100 same, the feed screw c^3 the support G to which the standard is attached while permitted sliding movement on the same toward the work, the clamping plates f^5 , and the main support H carried on the truck. 110

36. A channeling machine having a wheeled truck, a standard pivotally mounted at the side of the truck, an engine with its cross-head and cross-head guides thereon, means for adjustably feeding the same on 115 the standard toward the work, cutting appliances secured to the cross head and means for clamping the standard in any one of a plurality of positions for advancing the cutting appliances toward the work in the same direction with the action of the adjustable feed.

37. In a channeling machine, the combination with the frame A, of the swinging support G, the standard F having adjustment on the support G toward or from the work, the percussive tool e , the feed screw c^3 for feeding the tool toward the work, and the motor driving mechanism J and j for swinging the support. 125

38. In a channeling machine, the combination with a wheeled truck adapted to travel lengthwise the channel groove, of a main support sustained at the side thereof and 5 adjustable about an axis lengthwise the channel groove and adjacent the truck, a tool carrier mounted on the support and adjustable about an axis transverse the channel groove, motor driven means for swinging the carrier about said last named axis, a percussive tool and tool-actuating means on the carrier, means for feeding the tool and its actuating means toward the work, and means also for adjusting the carrier toward 10 or from the work on the support. 60
39. In a stone working machine, the combination with a frame, of a main support adjustable about an axis on the frame for angle cutting, a standard, an intermediate 20 support between said standard and said main support, said main support having longitudinal guide-ways for said intermediate support and gib connections overlying suitable flanges on the said intermediate 25 support to permit the adjustment of the latter toward or from the work, a tool and tool-actuating means on the standard, and means for forcibly feeding the same on the standard toward or from the work. 70
40. In a channeling tool, the combination with a wheeled truck, of a standard mounted at the side of the truck and substantially midway lengthwise the same, cutting appliances on the standard, means permitting adjustment of the standard about 35 an axis lengthwise the truck for cutting a channel groove having the requisite angle during progressive movement of the truck, and means for swinging the standard lengthwise the channel groove to cut along a path 40 at either end of and beyond the truck. 75
41. In a channeling machine, the combination with a wheeled truck, of a standard mounted at the side of the truck and substantially midway lengthwise the same, cutting appliances on the standard, a carrier 45 on which the standard is supported, means permitting adjustment of the carrier about an axis lengthwise the truck, means for swinging the carrier about an axis transverse the truck to swing the cutting appliances through a path at either end of and beyond the truck, means for feeding the cutting appliances on the standard toward the 50 work, and means for adjustably positioning the standard also on the carrier nearer to or farther from the work. 80
42. A channeler comprising a wheeled truck, a tool pivoted thereon, truck driving mechanism, a tool swinging mechanism, a common motor and means for rendering both said mechanisms at pleasure effective for applying the power of said motor to drive the truck and swing the tool, respectively. 85
43. A channeling machine having a truck, a swinging tool and a motor for simultaneously swinging the tool and driving the truck. 90
44. A channeling machine having a swiveled support, a tool carrier thereon, means to adjustably feed the tool on the carrier toward or from the work, means to adjust the carrier on the support toward or from the work, and means to swing the support 75 simultaneously with the cutting movement of the tool through a path extending at one end of and beyond the machine. 95
45. A channeler comprising a truck, a support on the truck cutting means pivoted 80 thereon, truck driving mechanism, means for securing the cutting means in fixed relation to or releasing it from the truck, and a motor effective both for driving the truck and swinging the cutting means. 85
46. A channeler comprising a wheeled truck, a standard pivotally supported at the side thereof, cutting means carried by said standard, means for feeding said cutting means toward or from the work, truck driving mechanism, means for securing the standard in fixed relation to the truck, and a single motor effective for simultaneously driving the truck and swinging the standard. 90
47. A channeler having a truck, a standard pivotally supported at the side thereof and adjustable to different angular positions about an axis lengthwise the channel groove, cutting means mounted on the standard, feeding means for feeding the cutting means toward or from the work on the standard, truck driving mechanism, means for securing the standard in fixed relation on its pivot or releasing the same, 105 and a single motor effective for simultaneously driving the truck and swinging the standard. 100
